TOBACCO HUMIDOR

José S. Lombard, New York, N. Y.

Application March 31, 1950, Serial No. 153,145

3 Claims. (Cl. 312—31)

1

This invention relates to humidors for storing tobacco and tobacco products, and particularly to humidors adapted to supply water vapor to the stored tobacco to control its moisture content. This application is a continuation-in-part of my earlier application Serial No. 587,510, filed April 10, 1945, now U. S. Patent No. 2,561,805, issued July 24, 1951.

In the storage of tobacco, it is important to prevent the tobacco from drying out and at the same to prevent it from becoming overly moist. It is also important that the tobacco be kept at a relatively low temperature to prevent the rapid loss of volatile flavors and aromatic substances.

In the usual tobacco humidor, a moist or wet surface is exposed to the closed tobacco chamber so that water evaporates from the surface until either the water supply is exhausted or the water vapor pressure reaches equilibrium at a value, depending upon the temperature of the chamber, which corresponds to one hundred percent relative humidity. This equilibrium condition will be disturbed each time the container is opened, but will be restored after closure. In the conventional humidor, it is ordinary practice to limit either the quantity of water available, or its rate of evaporation, to a value such that with the usual opening and closing of the humidor, the tobacco will not become overly moist. Limiting the supply of water has the disadvantage that the water must be replenished at frequent intervals, and limiting the rate of evaporation has the disadvantage that if the humidor is not opened for a considerable period of time, the tobacco may become too moist.

The present invention provides a humidor in which the relative humidity of an insulated tobacco chamber is maintained substantially constant irrespective of ordinary changes in the temperature of the surrounding atmosphere. One aspect of the invention is directed to permitting controlled amounts of water vapor to enter the tobacco chamber while preventing the entrance of water, or other material, in liquid form. Another aspect of the invention is directed particularly to the non-spill liquid container in combination with humidity-controlling agents. Other aspects of the invention are directed to particular features of construction for obtaining insulation on all sides of the tobacco chamber, for sealing the tobacco chamber, and for simplifying and lowering the cost of construction of the humidor. Other aspects, advantages, and objects of the invention will be pointed out in the following description or will be apparent therefrom when

2

considered in connection with the accompanying drawings, in which similar numerals refer to similar parts throughout the several views:

Figure 1 is a perspective view of the exterior of a humidor embodying the invention;

Figure 2 is a vertical sectional view of the humidor shown in Fig. 1;

Figure 3 is a perspective view of the removable cover of the humidor;

Figure 4 is a perspective view of a sealing ring;

Figure 5 is a perspective view of the outer shell of the humidor;

Figure 6 is a perspective view of the inner wall of the humidor;

Figure 7 is a perspective view of a cigarette rack adapted to be positioned within the tobacco chamber;

Figure 8 is a perspective view of a humidifying reservoir which is positioned between the outer and inner walls of the humidor;

Figure 9 is an exploded view of the reservoir shown in Figure 8;

Figure 10 is an enlarged partial sectional view taken on line 10—10 of Figure 2;

Figure 11 shows details of the float assembly of the reservoir of Figure 9;

Figure 12 is an enlarged sectional view taken along line 12—12 of Figure 9;

Figure 13 is a partial sectional view taken along line 13—13 of Figure 2;

Figures 14 to 18 are diagrammatic vertical sectional views of the reservoir showing the position of the humectant solution when the humidor is rotated about a transverse axis of the humidor extending through the reservoir; and

Figures 19 to 22 are diagrammatic sectional views showing the positions assumed by the humectant solution in the reservoir when the humidor, lying on its side, is rotated about its longitudinal axis.

As shown in Figures 1 to 6, a tobacco receiving chamber, generally indicated at 2, (Figures 2 and 6) is formed within the humidor by a cylindrical inner wall 4, which is provided with a removable wall lining 6, of Vinylite plastic or other suitable material. This wall 4 is positioned at its lower end around an upwardly extending shoulder 8 (Figure 2) formed by an inwardly extending circular boss 10 on the bottom of a generally cup-shaped outer shell 12, (see also Figure 5) the inner surface of the boss 10 being covered with a bottom lining 13 in the form of a disc of plastic material similar to that of the wall lining 6. This boss 10 preferably is formed by indenting the bottom of the shell 12 inwardly

so as to form an insulating dead air space 14 between the bottom of shell 12 and the surface (not shown) on which the humidor is placed. A ring 16, of cork or other suitable material, may be secured around the inset portion of the bottom so that the humidor rests on the ring 16 to prevent scratching or marring of the surface on which the humidor is placed.

The outer shell 12 extends upwardly around the inner wall 4, but is spaced therefrom so as to provide an insulating dead air space 18 around the tobacco chamber 2 between the inner wall 4 and outer shell 12.

The top of the air space 18 is closed by an annular sealing ring 22 (Figures 2 and 4) of generally U-shaped cross section, the outer downwardly extending edge 23 of which fits snugly within the shell 12 near its upper end. The ring 22 extends inwardly of the humidor over the upper edge of the inner wall 4 and its inner downwardly extending edge 24 fits snugly against the inner face of the wall 4 near its upper end, so that the lower edge of the ring 22 abuts the upper edge of the plastic lining 6.

The main body of the humidor, thus, is formed by the outer cup-shaped shell 12 surrounding the cylindrical inner wall 4, which is held firmly in position at its lower end by the shoulder 8 and at its upper end by the ring 22 that serves also to seal the dead air space 18. With this construction, the humidor can be assembled or disassembled by hand quickly and without need for special tools.

The humidor is provided also with an insulating removable cover, generally indicated at 26, (see also Figure 3) which seals the tobacco chamber 2 from the outside air and which provides an additional dead air space 28 above the tobacco chamber 2. The cover 26 includes a circular sealing plate 32 which is provided with a curved downwardly extending rim portion 34 completely surrounding the plate 32, the bottom edge of which abuts and preferably is flush with the upper edge of the shell 12, as at 36, when the humidor is closed.

As best shown in Figure 2, the inner surface of the lowermost portion of the rim 34 of plate 32, is substantially vertical, for example, for a distance of about one-eighth of an inch, and is arranged to form an air tight seal with the adjacent outer surface of the sealing ring 22, which surface also extends vertically for a short distance above the top of the outer shell 12. Above this sealing area of contact between the ring 22 and the plate 32, the sealing ring 22 curves inwardly more rapidly, that is, with a smaller radius of curvature, than does the sealing plate 32, so that the plate 32 separates immediately from the sealing ring 22, their only area of contact being immediately adjacent the upper edge of the shell 12.

In order to provide the dead air space 28 in the cover 26, a guide pan, generally indicated at 38, having a plane circular bottom 42 and an upwardly-extending outwardly-sloping annular wall 44, is secured to the under surface of the sealing plate 32, for example, by a screw 46 which extends upwardly through the bottom 42 of the pan 38, through a clearance opening in the sealing plate 32, and is in threaded engagement with a downwardly-extending boss 48 that is secured, by solder or other suitable means, to the inner surface of a dome-shaped handle 52. A cup-shaped weight 54, of lead or other heavy material, and a plane washer 56 are positioned

around the screw 46 between the sealing plate 32 and the guide pan 38 to prevent bending of the guide pan when the screw 46 is tightened and to provide sufficient weight in the cover 26 to insure that it will seat itself properly when placed on the humidor.

The handle 52 is generally circular in shape, but of course may be formed in any other desired shape, and is provided with a downwardly-extending annular flange 58 which is curved inwardly so that the cover can be gripped easily with the fingers, the bottom portion of the flange 58 being curved outwardly so that its undersurface lies flush on the upper surface of the sealing plate 32. The handle 52, sealing plate 32, and guide pan 38 are locked firmly together by the screw 46.

When the cover 26 is being placed on the humidor, the sloping wall 44 of the guide pan 38 slides against the inner corner of the sealing ring 22 and insures proper positioning of the cover. The seal formed by the rim 34 of the sealing plate 32 and the outer surface of the sealing ring 22 insures adequate protection of the stored tobacco

from the outside air, and at the same time permits easy removal and replacement of the cover because the seal is broken when the cover has been tilted or lifted only a short distance so that there is no tendency for the cover to bind or jam.

It will be noted also that the tobacco chamber is insulated on all sides by dead air spaces, insuring that the tobacco will remain relatively cool even though the humidor is surrounded temporarily by warm air.

The tobacco chamber 2 can be used for storing tobacco products in any form, for example, cigarettes, cigars, or pipe tobacco. In order to provide a convenient support for cigarettes, a generally U-shaped rack, generally indicated at

40 62 in Figure 7, is adapted to fit within the tobacco chamber 2. The rack 62, which may be formed of metal, plastic, or other suitable material preferably in one piece, comprises a bottom 64 and vertical sides 66, both of which are provided with inwardly-extending flanges 68 to hold the cigarettes in position. The sides 66 are perforated to permit vapor to enter the ends of the cigarettes, and are provided at their upper ends with outwardly-extending curved ears 72 which fit loosely within the tobacco chamber 2 to position the tray centrally thereof while permitting it to be rotated by hand to any desired position. This rack may be similar in all respects to that described in my above-mentioned co-pending application.

In order to provide water vapor for the tobacco chamber 2, a reservoir, generally indicated at 76 in Figure 8, of sheet metal or other suitable material, is positioned within the humidor between the inner wall 4 and the outer shell 12.

In order to provide a passageway for the water vapor in the reservoir 76 to enter the tobacco chamber 2, a curved inner cover 78 (Figure 9) of the reservoir 76 is provided with a perforated cup 65 or strainer 80 which is secured into an opening 79 of the cover 78 so as to extend into the interior of the reservoir 76. This strainer 80 is provided with a cover 81 which is secured over the open face of cup 80 by any suitable means, for example, by press-fitting the flange 81a of the cover 81 within the walls of the cup 80. The cover 81 is provided with perforations, which desirably are somewhat smaller than the perforations in the body of the strainer 80. The perforated strainer 80 is positioned adjacent an

70 75

opening 82 in the inner wall 4 (Figure 6) which is covered by a perforated sheet or screen 84 of plastic, metal, or other material, interposed between the inner wall 4 and the plastic lining 6. A hole 86 in the plastic lining 6 immediately adjacent the screen 84 permits the water vapor to pass into the tobacco chamber 2. The lining 6 fits sufficiently loosely within the inner wall 4 that it may be rotated by hand, thus permitting more or less of the perforated portion 84 to overlap the opening 86 in the lining.

In order to control the relative humidity within the chamber 2 so that it is substantially independent of the temperature outside the humidor, the reservoir 76 is partially filled with a humectant solution 88 (Figure 14). In humidors intended to maintain a relative humidity of 70 to 75 percent, usually considered desirable for the storing of cigars, the humectant solution 88 comprises equal parts by weight of sodium acetate and ethylene glycol with two parts by weight of water. This solution will maintain the desired relative humidity substantially constant, so that cigars which are overly dry when placed in the humidor will acquire the desired moisture content, whereas cigars which are overly moist when placed in the humidor will lose part of their moisture to acquire the desired moisture content. The humidity-controlling agents, that is, sodium acetate and ethylene glycol, are substantially non-volatile and so never need to be replaced in the reservoir. If the humidor were not opened, the water also would last indefinitely, but with normal usage when the humidor is periodically opened and closed a certain amount of water vapor will be lost and water must be added to the reservoir from time to time. The humectant solution 88 has no deleterious effect on the flavor or aroma of the tobacco.

It has been found that the humectant solution 88 will effectively control the humidity even when its water content has decreased to as low as 2 to 5 percent of the humectant solution. However, if the percentage of water drops below this amount, the water in the reservoir must be replenished or the humidity-control system will not function properly. An arrangement is provided in the reservoir 76 for indicating when the water supply is low and for permitting water to be added. In addition, an arrangement is provided which prevents the humectant solution 88 from leaking out of the reservoir 76 if the humidor is turned on its side or even if it is turned upside down. This latter feature is particularly important because of the presence of the non-volatile humidity-control agents in the humectant solution which desirably are retained in the humidor throughout its life, and which would contaminate the tobacco if allowed to enter the chamber 2.

The reservoir 76 includes a cup-shaped portion, generally indicated at 90, (Figure 9) formed, for example, from one piece of metal or other suitable material, which includes an outer face 92, and side walls 94. The inner cover 78 of the reservoir is provided with flanges 96, which fit snugly within the walls 94 and are sealed thereto so as to be water-tight, as for example, by soldering. The walls 94 are provided with outwardly-extending flanges 98 which fit under projecting tabs 102 (Figures 6 and 10) on the outer surface of the inner wall 4 to support the reservoir. The face 92 and the cover 78 are curved so as to fit nicely between the inner wall 4 and the outer shell 12, as shown in Figure 13.

A filler-tube and indicator, generally indicated at 104 in Figure 9, is positioned in the reservoir 76 and includes a tube 106, extending from within the reservoir 76 upwardly through a suitable opening in the top wall thereof, which is terminated at its upper end by a fitting 108, for example, formed of a separate piece of metal and attached to the filler tube 106 as by press fitting (see also Figure 10). The fitting 108 forms an internal valve seat 112, whose purpose will be explained later, and an external shoulder which presses downwardly against a washer 114 of rubber, or other suitable material, which surrounds the filler tube 106 to form a water-tight seal. The upper end of fitting 108 is recessed to form a smaller diameter projecting portion 116 which extends into an opening 118 (see also Figure 4) in the upper surface of the sealing ring 22.

The lower end of the filler tube 106 is closed by a cup 122 which extends upwardly around the outside of the tube 106. The bottom of the cup 122 is provided with a small clearance opening to permit passage of a float rod 128, as will be explained later. The cup 122 is provided with an opening 129 in the side opposite the center of the humidor, for example in the form of two vertical slits in the wall of the cup 122. Water which is poured into the filler tube 106 through the opening 118 in the sealing ring 22 passes through a perforated metal disc 130 in the tube 106 and enters the reservoir 76 through the opening 129.

In order to prevent leakage of the humectant solution out of the humidor, even if the humidor should be inverted, a check valve including a movable plunger 131 is mounted within the cup 122. The plunger 131 has the shape of a relatively thick washer with a central opening for the float rod 128 and concave upper and lower surfaces. This plunger is fitted loosely within the cup 122 so that it is free to move along the rod 128 when the humidor is inverted and seat against the perforated disc 130 to prevent the humectant solution from entering the tube 106. This arrangement is satisfactory because at most only one or two drops of solution will be trapped in the cup 122 and will not have sufficient hydrostatic pressure to force the solution past the plunger 131 and through the perforations of the disc 130.

In order to indicate when the humectant solution 88 has reached such a low level in the reservoir 76 that it should be replenished, a hollow cylindrical float 136 (see also Figure 11) is provided, which may be formed, for example, of two metal cups 138 and 142. The cup 138 is provided with a peripheral groove 144, formed by embossing the metal shell inwardly, and is adapted to fit over the open end of the cup 142, the groove 144 serving as a stop against which the cup 142 is positioned. The joint between the cups 138 and 142 is sealed by any suitable means, as, for example, by soldering. It is apparent, of course, that the float 136 can be constructed in any other known manner and of other materials. The lower end of the float rod 128 is secured to the float 136, as by being positioned around the groove 144, and extends upwardly through the clearance opening in the bottom of cup 122 into the filler tube 106 and is fitted at its upper end with an indicator ball 146 of plastic or other suitable material. It is apparent that as the level of the humectant solution in the reservoir 76 changes, the ball 146 will move upwardly or downwardly within the filler tube 106 (Figure 10).

This ball, when it is near the top of the filler tube 106, is visible through the opening 118 in the sealing ring 22, indicating that there is sufficient water within the reservoir 76. This ball 146 may be colored, if desired, in order to enhance its visibility.

An annular boss or ring 148, formed, for example, by embossing a groove in the outer surface of tube 106, projects inwardly of the filler tube 106 a short distance below its upper end, and also may be colored so that it is readily visible through the opening 118 in the sealing ring 22 whenever the ball 146 is below the ring 148. Thus, whenever the ring 148 is visible, an indication is provided that additional water is needed for the reservoir.

The indicator ball 146, in conjunction with the valve seat 112 of the fitting 108, forms a check valve so that if the humidor should be inverted, the force of gravity will move the float assembly downwardly seating the ball 146 against the valve seat 112 and preventing the humectant solution from leaking out of the reservoir.

When a non-volatile humectant solution is used, such as in the present humidor, it is important not only that none of the liquid spill outside the humidor, but also that none of the liquid be admitted to the tobacco chamber where, because of its non-volatile character, it would permanently contaminate the tobacco products therein. The construction of the humidor in accordance with the present invention prevents direct spilling of the humectant solution either outside the humidor or into the tobacco chamber.

Figures 14 to 22 will be helpful in explaining this non-spill action. Figure 14 shows the position of the humectant solution 88 when the humidor is in its usual upright position, the level of the humectant solution 88 being maintained at all times below the level of the perforated cup 80. The positions assumed by the humectant solution when the humidor is tipped to the left or right are shown in Figures 15 and 18, respectively. Continued rotation of the humidor about its transverse axis causes the reservoir 76 to assume the positions shown in Figures 16 and 17, the humectant solution at all times remaining below the level of the perforated cup 80. It will be noted also that when the humidor is approximately upside down, that not only is the end of the filler tube 106 out of the humectant solution, but plunger 131 has been pulled by gravity against the disc 130 to prevent the solution from entering the tube 106, and the float assembly has been pulled downwardly by gravity causing the ball 146 to seal the entrance to tube 106 so that even if any of the liquid were accidentally trapped within the tube 106 it will not leak out. The perforated cup 80 extends within the reservoir and the openings are so small that it is difficult for any of the humectant solution to enter the cup in liquid form; however, even if this should occur, the liquid would be prevented from entering the tobacco chamber by the even finer perforations in the cover 81 and would merely leak back through the perforations in the body of cup 80 into the reservoir.

When the humidor is positioned on its side, that is, with its longitudinal axis horizontal, the reservoir 76 may assume the positions shown in Figures 19 to 22. When the reservoir is on top of the humidor, as shown in Figure 19, the humectant solution drains to the two ends of the reservoir so that the level of the liquid is below the perforated cup 80 and cannot leak into the tobacco

chamber 2. If the humidor is rotated so that the reservoir 76 is on the bottom as shown in Figure 20, the level of the liquid is well below the perforated cup 80. If the humidor is rotated so that the reservoir 76 is on the side of the humidor, as shown in Figures 21 and 22, the level of the humectant solution 88 remains below the perforated cup 80.

Thus, irrespective of the position of the humidor, the humectant solution 88 cannot spill out of the reservoir, and the non-volatile humidity control agents therein will last indefinitely.

It will be noted also that the perforations of the cover 81 of the cup 80 are spaced from the perforations of screen 84; thus, fluid motivated by capillary forces cannot pass readily from one screen to the next and thus enter the tobacco chamber. Moreover, the perforations of cup 80 and its cover 81 in the front 78 of the reservoir, are preferably sufficiently small that the humectant liquid, even if splashed against the screens, will not pass through the perforations.

Thus, it will be seen that the foregoing humidor with its humectant solution and non-volatile humidity-controlling agents is well adapted to attain the ends and objects hereinbefore set forth. Humidity control substantially independent of the ambient temperature is provided by the humectant solution, it being understood, of course, that other humectant solutions having non-volatile control agents can be employed, if desired, and that the solution can be adjusted to provide other relative humidities than that suggested, for example, for the storage of cigarettes or pipe tobacco. The non-spill characteristics of the humidor make practicable the use of such non-volatile agents. The insulating properties of the humidor, wherein the tobacco chamber is surrounded on all sides by a dead air space, assists in providing more precise control of the humidity and prevents the tobacco from becoming too warm or too cool with consequent loss of the aromas and volatile flavors.

I claim:

1. In a humidor having a tobacco receiving chamber, substantially cylindrical spaced walls surrounding and defining said chamber, and a reservoir having inner and outer walls containing a humectant solution and positioned between said spaced walls of said chamber for supplying water vapor to said chamber, a combination comprising an opening extending between said reservoir and said chamber for permitting water vapor to pass from said reservoir into said chamber and from said chamber into said reservoir, the inner and outer walls of said reservoir being curved and defining portions of concentric cylinders, said opening extending through the said inner wall of said reservoir substantially at the center thereof and having a circumferential lip therearound extending within said reservoir, said opening being at all times above the level of a predetermined quantity of said solution in said reservoir when said liquid is at rest, irrespective of the orientation of said humidor, and an indicator responsive to the level of said solution and arranged to denote when said predetermined quantity of liquid is in said reservoir.

2. Apparatus as claimed in claim 1 including an internal annular lip on the inner reservoir wall extending around said opening and inwardly of the reservoir, and a screen having a plurality of minute holes extending across said opening.

3. Apparatus as claimed in claim 1 including a filler tube having an upper opening and a

lower opening and extending into said reservoir, said indicator being positioned within said tube and including a float positioned within said reservoir, a float rod extending upwardly from said float into said filler tube, and a ball mounted on said float rod and visible through said upper opening of said filler tube, and a valve set within said filler tube arranged to be closed by upward movement of said ball to seal said upper opening when said liquid reaches said predetermined level.

JOSÉ S. LOMBARD.
